UNITED STATES PATENT OFFICE

2,457,266

GUN PRIMER MECHANISM

John R. Oliver, Beverly, Mass., assignor to United Shoe Machinery Corporation, Flemington, N. J., a corporation of New Jersey

Application July 20, 1945, Serial No. 606,048

8 Claims. (Cl. 89—27)

1

This invention relates to primer mechanisms of ordnance in which projectiles are separate from the powder charge as distinct from ordnance using fixed ammunition.

With medium or larger size guns using separate loading ammunition, the breech member must be provided with some means of preventing powder gases from passing to the rear into the threads and other accurately made parts of the breech mechanism. The erosive power of such gases is such that a gun would soon be rendered useless if a sealing means were not made effective. However, such sealing means must afford a passage for the flame of the primer to pass through the powder charge of the gun. The invention is more especially, although not exclusively, intended for use as a primer mechanism to be mounted upon a breechblock carrier, the latter being adapted to support the breechblock in both swinging and rotative motion during opening and closing of the breech. In such an installation, the breechblock is provided with an obturator (of the De Bange type) having an axial vent for the primer flame and the rear portion of the obturator vent necessarily has associated therewith a primer mechanism which is as reliable, convenient and close fitting as possible in operation.

It is an object of the present invention to provide an improved primer mechanism as a complete unit which may be mounted on a breechblock carrier in which mechanism a single swing of an operating handle will positively and firmly enclose a primer in position for firing.

Another object is to provide an improved structure for ejection of the primer shell from a primer holder that is retained in firing position.

Still another object is to provide a positive lock as a safety device to prevent untimely movement of the firing pin while the primer mechanism operating handle is actuated or the breechblock is moved.

Another object is to provide parts of the primer mechanism which are so formed as to facilitate the insertion of a new primer, whereby such primer may be subsequently pressed home into firing position by the operation of the primer mechanism.

For the purposes in view and in accordance with various features of the invention, the illustrated mechanism is shown in fixed association with an obturator and breechblock carrier of conventional type. A feature of the invention consists in an inner and outer block arrangement within a frame which is easily demounted from the obturator and carrier, the block arrangement

2

serving to wedge home and enclose a primer in firing position. Another feature is the provision of a curved wedge for operating the primer shell ejector. Another feature consists in the novel arrangement for positively locking the firing pin in a position away from the primer until deliberately released by operation of the firing mechanism. Still another feature consists in the parts of the primer mechanism which cooperate to form a trough by means of which insertion of a new primer is facilitated.

The above and other features of the invention, including novel details of construction and combinations of parts, will now be more particularly described in connection with the accompanying drawings and pointed out in the claims.

In the drawings,

Fig. 1 is a plan view, partially in section, of the primer mechanism as installed on a gun with a conventional breechblock and obturator;

Fig. 2 is an elevational view of the primer mechanism shown in Fig. 1;

Fig. 3 is a left side view of Fig. 2 in elevation;

Fig. 4 is a sectional view along the line IV—IV of Fig. 3;

Fig. 5 is a sectional view through parts of the primer mechanism casing with other parts shown in full and dotted lines clearly to show the theory of operation;

Fig. 6 is a plan view partially in section along the line VI—VI of Fig. 5;

Fig. 7 is a sectional view along the line VII—VII of Fig. 5;

Fig. 8 is a sectional view similar to that of Fig. 4 but showing the parts in positions assumed for reception of a new primer;

Fig. 9 is a plan view of the parts shown in Fig. 8; and

Fig. 10 is a perspective view for purposes of clarity, drawn to a reduced scale, of a block used in the mechanism.

In medium or larger size guns it is well known to use an obturator with a breechblock 10 and a gun tube 11 as shown in Fig. 1 which obturator comprises a steel mushroom head 12 against which the force of the explosion longitudinally to the gun is exerted, a resilient or elastic pad 14, split rings 15, a steel disc 16, and a spindle 18. The spindle of an obturator of this type is fitted within the breech block 10 and pressure of the gases against the mushroom head 12 upon firing compresses the elastic pad 14 and further presses the split rings 15 surrounding the spindle against the walls of the bore thus effectually preventing leakage. Breechblocks are conventionally

mounted to rotate independently of the obturator parts and, because of this, any sticking of an obturator to its seat in the gun tube 11 will not interfere with the rotation of the block 10 when opening the breech. After proper rotation of a breechblock 10 to disengage the usual interrupted threads 19, the block 10 and obturator may be readily withdrawn from the gun tube 11. An obturator spindle 18 of this type is provided with a vent 20 passing through its full length, permitting passage of a flame from a primer 22 to the powder charge in the gun. A sleeve 24 forms a pintle upon which the breechblock may rotate and this sleeve 24 forms a part of the breechblock carrier 25, which supports the breechblock for movement into and away from the gun. The spindle 18 is keyed at 23 to the pintle 24 preventing the spindle's rotation. A helical spring 26 serves to hold the obturator firmly in place within the breechblock 10 and is located in a recess of the sleeve 24 surrounding the spindle 18 and bearing against an inserted primer mechanism, the particular one here disclosed being generally indicated as 28 in Fig. 1. The primer mechanism 28 here spoken of embodies the subject matter of this invention and will now be described.

The primer mechanism 28 comprises an exterior box-like frame 30 having a cylindrical portion 32 (Figs. 1, 6, and 9) adapted to extend in close fitting relation with the recess of sleeve 24 (Fig. 1) and having a shoulder 34 against which the spring 26 may bear. Interrupted nonhelical elements 36 (with no lead) are provided within the cylindrical portion 32 to engage with and disengage from cooperating interrupted elements on the end of obturator spindle 18. A hollow exterior threaded nut 40 is screwed within the portion 32 and one end 42 thereof is adapted to abut the end of obturator spindle 18 as a positive stop. As interrupted elements 36 have no lead, shoulder or end 42 serves as a stop determining the innermost position of the primer mechanism both before and after the elements 36 are engaged. Nut 40 also serves as a supporting means for a cylindrical plug member or nipple 44 which is bored to serve as a holding or retaining means for the primer 22 and is threaded at 45 for attachment to the spindle. The box-like frame 30 has an upstanding flange 46 the position of which is determined on the gun with respect to the primer opening by a stud 48 (Figs. 2, 3, 4 and 8). Within the frame 30 are supported two juxtaposed blocks an inner block 50 and an outer block 52 both arranged to rotate to a limited degree about a non-rotative pin 54 mounted in the casing 30 and held by a set screw 55 (Fig. 6). A handle 56 is arranged to swing upon the pin 54 and integral with the handle 56 is a plate 58 to which the outer block 52 is attached by means of bolts 60. The outer block 52 swings in guideways 62 and 64 formed in the frame 30. The inner block 50 is slidably engaged by sloping hook-shaped flanges 66, 68 on the outer block 52 (see Figs. 3, 4 and 6). The handle 56 is provided with a latch member 70 pivoted at 72 within a recess 74 of the handle (Fig. 2). The latch member 70 has a hook 76 adapted to engage a plate 80 adjustably positioned upon the frame member 30 by means of a cap screw 82 and a lock pin assembly 83 (Fig. 3). A resilient member 84 is mounted to bias the latch 70 into latching position. The inner block 50 is provided with a pin 90 which is adapted to travel along a curved slot 92 formed in a vertical portion 94 (Fig. 5) of the casing 30.

The portion 94 is actually a thickened continuation of the flange 46. It is to be noted that the left-hand slot 92 (as viewed in Fig. 4) has a rather short radius of curvature with a center 5 on the longitudinal center line of inner block 50. A right-hand slot 96 is so curved as to be concentric with the pin 54. Attached to the plate 58 by screws 97 is a shelf plate 98 having a peculiar configuration, as shown in Fig. 4, and adapted to be rotated with and by the handle 56. The inner block 50 is provided with a rearward extending projection having a surface 108 as clearly shown in Fig. 10. A cover plate 102 is attached to the casing 30 by screws 104, 106 and 108 (Fig. 2), and said plate 102 has a V-shaped notch 110 at the bottom of which is at all times concentric with the center of the primer opening, as shown in Fig. 2. Plate 102 joins and braces the two sides of the casing 30. The ejector lever 120 is mounted on a pivot 122 and it is urged counterclockwise around this pivot by a curved finger or wedge 124 which is adapted to swing with the parts carried by the handle 56. The curvature of finger 124 is such that when the cam surface of the finger 124 contacts the ejector lever 120 upon lowering of the handle 56 a pull is imparted to the primer shell by the ejector lever after the two blocks 50 and 52 have moved far enough down to free the primer shell.

30 A special safety lever 128 (Figs. 3, 5 and 10) is provided with a forked end 130 which engages a groove in the firing pin 132, these parts being mounted within the inner block 50. This lever 128 is pivoted at 134 on the inner block 50 and is held in its operative position by the engagement therewith of a hump 136, which is part of a lever in the firing mechanics shown in Fig. 5 and contained within the outer block 52.

40 The firing mechanism comprises a hammer 140 urged in a clockwise direction in Fig. 5 by a vertically disposed spring 142. Rigidly connected with the hammer 140 to cock it and then release it is a lever 144 having a shoulder portion 146 against which abuts one finger of a V-shaped pivoted member 148. The member 148 is pivoted on the end of an arm 150 (which is adapted to rotate with the hump 136) and said arm 150 is actuated by a depending lever 152 having a ball-shaped lower end which engages a notch 154 in a slide 156 operated by a lanyard 158. A leaf spring 160 is mounted to bias the member 148 upward or counterclockwise about its pivot, as viewed in Fig. 5. The lanyard is biased toward the gun by a resilient member 162 mounted within a depending portion 164 of the casing 30.

50 With the parts shown in their positions of Fig. 5 a pull on the lanyard 158 will remove the hump 136 from the path of the lever 128 (thereby unlocking the firing pin 132) and cause the member 148 to rotate hammer lever 144 counterclockwise in Fig. 5 against the compression of spring 142 thereby cocking the hammer 140. Further movement outwardly of the lanyard 158 will cause member 148 to slip by the shoulder 146 with the result that spring 142 will urge the hammer 140 into engagement with the firing pin 132 and fulfill the primer 22. Care must be taken that the movement of the firing pin is not great enough to dent the primer more than 20 thousandths of an inch. If the movement is greater than this it will break a hole through the casing of the primer cartridge and provide an opportunity for leakage of the gas after the firing of the main charge. It will be understood that in

large guns the force of the gas is tremendous and may amount to 35,000 or more pounds per square inch.

In removing the spent primer shell, the handle 56 is first unlatched from the plate 80 and moved downwardly. The outer block 52 swings or slides down angularly in one plane at the same rate as the handle 56 but the inner block 50 swings down at a slower rate due to the engagement of the pin 90 in the slot 92. During the first part of the downward movement of inner block 50 it tilts slightly from the position shown in Fig. 2 to the position shown in Fig. 4. During this time, however, the inner block 50 undergoes a very considerable movement out and up from the outer block 52 within the guides 66 and 68 of the outer block 52 and also out or rearward from the primer 22, and this movement continues until the pin 90 has reached the position shown in Fig. 4. Further downward movement of the lever 56 causes the curved finger 124 to urge the ejector lever 120 rearward and forcibly eject the primer shell past the two blocks 50 and 52 and from the piece. It is to be understood that a considerable force (about 150 pounds or over) is required to dislodge a spent primer from the plug 44. As can be seen in Fig. 3 the curved finger 124 is so formed that the ejector lever 120 may be moved out slowly with great force as handle 56 is moved downwardly and then a shoulder 125 serves to give a sharp outward fling of lever 120 in order to throw the primer shell out as the parts reach the positions shown in Fig. 8. When the lever 56 is in its lowermost position the inner block 50 will be in the position as shown in Fig. 8 and it is to be noted that plate 98 and shelf 100 cooperate with the V-shaped notch 110 to facilitate the insertion of a new primer shell. The new primer shell is firmly forced home into firing position by the wedge action of the outer block 52 upon the inner block 50 as the handle 56 is again moved up into latched position. The inner block 50 approaches its position adjacent the block 44 (Fig. 6) and engages the primer with a flat surface and leaves no chance for a point contact or cam action upon the primer—i. e.—the block 50 engages the primer fully and firmly.

When a primer mechanism 28, constructed as disclosed herein, is to be assembled in association with a breechblock 10, the cylindrical portion 32 of the primer mechanism casing 30 is inserted within the recess of the breechblock carrier sleeve 24 against the compression of spring 26 until stopped by the end 42 of the nut 40 meeting the end of the obturator spindle 18. The interrupted nonhelical elements 36 are divided longitudinally of the spindle 18 into plain and grooved sectors and they permit relative axial movement of portion 32 and spindle 18. The primer mechanism 28 is then turned to lock the portion 32 and spindle 18 together by means of the elements 36 and stud 48 (Fig. 2) is inserted to hold the parts in their assembled positions on the breechblock. Full engagement of the elements 36 may be assured as the obturator spindle 18 is nonrotatively keyed to the sleeve 24.

Having described my invention, what I claim as new and desire to secure by Letters Patent of the United States is:

1. A primer mechanism for ordnance including a demountable frame with means for attaching the same to a breechblock carrier and obturator and containing outer and inner blocks holding the firing pin and hammer operating mechanism, a handle pivoted to said frame for angularly slid-

ing the outer block relatively to the frame and inner block and in one plane, and guiding means on the outer block extending in a second plane and constituting a wedge engaging the inner block whereby a sliding movement of the outer block may guide the inner block toward or away from a primer plug of said obturator.

2. A primer mechanism for ordnance including a demountable frame with means for attaching the same to an obturator spindle, means within said frame for retaining a primer in firing position, said means including a plug for holding said primer and two juxtaposed blocks carrying a firing pin and hammer mechanism, both blocks being slidable in said frame, one of said blocks being guided and wedged by the other block to press the primer into said plug, motion of the blocks being imparted by a handle pivoted to said frame.

3. A primer mechanism for ordnance including a demountable frame with means for attaching the same to an obturator spindle, means within said frame for retaining a primer in firing position, said means including a plug for holding said primer and two juxtaposed blocks carrying a firing pin and hammer mechanism, both blocks being slidable relative to each other in said frame, one of said blocks being guided by the other block to press the primer into said plug, a handle for moving the blocks within the frame, an ejector member mounted on said frame to engage the primer in the plug, and a wedge member movable with said blocks to operate the said ejector member.

4. A primer mechanism for ordnance including a demountable frame with means for attaching the same to a breechblock and carrying means for holding a primer in firing position, an inner block carrying a firing pin and an outer block carrying a hammer operating mechanism, said outer block being pivotally mounted on the frame and having guiding means for pressing home the primer by means of the inner block, said frame having a movable member arranged to trip the hammer operating mechanism, and a locking means associated with said firing pin arranged to be inoperative upon tripping movement of the movable member.

5. A primer mechanism for ordnance including a demountable frame with means for attaching the same to a breechblock and carrying means for holding a primer in firing position, an inner block adjacent to said holding means and carrying a firing pin, an outer block separated from said holding means by said inner block and carrying a hammer operating mechanism, said outer block being pivotally mounted on the frame and having guiding means for wedging home the primer by means of the inner block, and latching means for holding the two blocks in wedged relation against the primer in said holding means.

6. A primer mechanism for ordnance including a demountable frame with means for attaching the same to an obturator spindle, means within said frame including a plug with an opening for holding said primer, and two blocks mounted independently of said plug and carrying a firing pin and hammer mechanism, both blocks being slidable relative to each other in said frame to expose the primer opening and having cooperating surfaces forming a trough leading to the primer opening while the latter is exposed.

7. A primer mechanism for ordnance using separate loading ammunition, said mechanism

including a demountable frame constructed for attachment to a breechblock carrier, said frame carrying a primer holding block arranged to be placed in alinement with an obturator, juxtaposed inner and outer blocks arranged for sliding relative to the primer holding block and to each other and also within said frame, and a manually operable handle for forcibly moving one block against the other and urging the latter toward the primer holding block.

8. A primer mechanism for ordnance using separate loading ammunition, said mechanism constituting a complete unit and including a demountable frame constructed for direct attachment to an obturator and breechblock carrier, said frame enclosing a primer holding plug, an inner block arranged to slide in a direction running transversely and longitudinally to said plug, and an outer block pivoted to said frame, and said outer block being formed to exert a

wedge action on the inner block to actuate the latter.
